RADIO GUIDING SYSTEM

Louis John Heaton-Armstrong, London, England,
assignor to Standard Telephones and Cables
Limited, London, England, a British company

Application June 24, 1943, Serial No. 492,081
In Great Britain July 30, 1942

8 Claims. (Cl. 250—11)

The present invention relates to a radio beacon for radio guiding systems of the kind in which a field distribution or field strength pattern is commutated so as to produce complementary signals, for example A-N signals to the right and left of the course respectively, and on the course a continuous dash or no-signal.

Hitherto radio beacons for systems of the type specified which have been largely employed comprise a central energised antenna and two reflector antennae laterally disposed with respect to the central antenna. The two reflector antennae are keyed alternately so as to cause the radiation pattern produced by the beacon to oscillate about the course line in a now well known manner. The great advantage of such a beacon is its simplicity. It is very easy to set up on a new frequency and alignment and tuning is not unduly difficult. The aerial spacing is not changed over the frequency band from 30-40 megacycles per second.

Simplicity is, however, paid for by the following disadvantages:

1. The beam width cannot be made less than $2\frac{1}{2}^{\circ}$ whatever the reflector spacing. Modern conditions call for a beam width of the order of $.5^{\circ}$ to 1.5° .

2. Critically timed keying relays are necessary.

3. Careful lining up is necessary in order to avoid key clicks.

4. It is difficult to get both back and front beams free from key clicks.

5. The field distribution pattern is of such a shape that the likelihood of splits in the beam due to reflections from the hangars, trees, etc., is considerable.

The present invention has for its object to provide a radio guiding system in which all these disadvantages are absent whilst retaining simplicity of the system, and without introducing any further disadvantages.

According to one aspect of this invention, a radio beacon of the type hereinbefore specified comprises three antennae arranged at a distance apart and each fed directly from a source of high frequency currents phased with respect to each other and a single "make" or "break" contact device for commutating the field strength pattern formed by said antennae.

According to another aspect of the present invention a radio beacon for a radio guiding system of the kind specified hereinbefore comprises three linear antennae mounted above the ground and symmetrically located with respect to the desired course, means for feeding the outer an-

tennae with currents in opposite phases, and for feeding the centre antennae with currents of the same frequency and with a phase angle of 90 degrees or less with respect to the current in either of the two outer antennae and means for changing the relative phases of the centre and outer antennae from a phase lead to a phase lag or vice versa to produce the commutation of the field strength pattern.

10 In a preferred embodiment of the invention the radio beacon comprises three vertical dipole antennae mounted approximately one half-wave length above the ground in alignment perpendicular to the desired course, the two outer antennae being at equal distances from the centre antenna which is located on the course line, all the dipoles are centre fed, from the same source of high frequency current, the two outer dipoles being fed in phase opposition and the centre dipole being fed with current having a phase angle of 90 degrees or less with the currents in either of the outer dipoles. Means is provided to change the phase of the current in the centre dipole, for example by 90° or 180° so that with respect to the currents in one of the outer dipoles the current in the centre dipole alternately leads and lags and with respect to the currents in the other outer dipole, the current in the centre dipole alternately lags and leads respectively.

15 20 25 30 35 40

20 The distance between the outer dipoles and the centre dipole and the phase angle between the energising currents is so chosen to give the practical minimum beam width, that is the width of the overlapping portion of the field strength patterns in its two commutated positions. In one particular example, the distance between the outer dipoles and the centre dipole is $.475$ of the operating wave length and the phases of the currents in the three dipoles are respectively 0° , 45° and 180° and alternately due to keying 0° , 315° and 180° . A single "make" or "break" contact device is employed for effecting this commutation of the field strength pattern.

45 The invention will be better understood from the following description taken in conjunction with the accompanying drawings in which,

Figure 1 shows diagrammatically a preferred embodiment of the invention;

Figure 2 shows the circuit arrangements used in the embodiment shown in Figure 1;

Figures 3A-D and 4A-D are explanatory diagrams used in the description.

Referring to Figure 1, the transmitter T is connected to an open wire line TD. The radio frequency power splits up at D and is fed to the

three dipoles A, B and C, the distance between AB and BC being .475 the operating wave length. The open wire lines DA and DC have each a length equal to one and a quarter wave lengths and the open wire line DB is three-quarters of a wave length long. Lines DA and DC are deliberately made an odd multiple of quarter wave lengths as the currents then fed to the dipoles will remain constant in phase and magnitude, in spite of the fact that their impedance changes due to the effect of the changing phase of the centre aerial current on keying. The dipoles A and C are connected to opposite sides of the lines in order to get the 180° phase difference of the currents in them. Keying is done by means of a single contact relay REL1 which will be described more fully in relation to Figure 2. The dipoles themselves have a length, of course equal to one half or approximately one half the operating wave length.

Referring now to Figure 2, the transmitter feeds into a 500 ohm line TD by means of a transformer TR having tuned primary and secondary windings. LIC3 is a circuit for suppressing parallel currents on the line TD, capacities C1, C2 and C4 and inductances L2, L3 form a network for feeding the operating current from supply S to the relay REL1 along the line, thus eliminating the requirement of a separate cable. The keying mechanism is represented as a key K, and connects the source S to the line TD through the inductances L2, L3.

Keying is effected by shunting a reactance across the centre dipole. Since the line length DB is an odd number of quarter wavelengths, the effect of the reactance is to change the phase of the current fed to the centre dipole. By using a reactance equal in magnitude to the antenna resistance, and changing the reactance from capacitive to inductive and vice versa, a phase change of 90° is obtained whilst maintaining a constant current in the antenna. In Figure 2 the keying unit consists of an adjustable inductive-loop L4 of, for example 70 ohms impedance and a capacity C5 of 140 ohm impedance which is placed in series with the inductance. The relay REL1 when operated short circuits the condenser C5 by closing the "make" contact r1. This converts the impedance across the dipole from 70 ohms capacitive reactance to 70 ohms inductive reactance. C6 is a blocking condenser to prevent the relay short circuiting its operating current, L5 is a choke coil to keep the radio frequency energy from the relay winding W.

The principle of operation of the beacon according to the invention is as follows, reference being made to Figures 3 and 4.

Consider three antennae A, B and C (Figure 3A) fed with currents I_A, I_B and I_C having the phases shown in Figure 3A. These currents will give rise to fields F_A, F_B, F_C at point P at a great distance away. F_A and F_C cancel each other since they are in phase opposition.

If we move from P to P₁ also at a great distance away and near the approach path with dipole B as centre, the field from B will be unchanged in magnitude and phase, while that from A will be retarded and that from C will be advanced as compared with the phases at P. The outer dipoles will then form at P₁ a resultant field F_{AC} which is always 180° substantially out of phase with F_B as shown in Figure 3C. As we move round the antenna B the resultant F_{AC} varies. On moving to the "A" side of the antenna B, F_{AC} changes 180° in phase and is then in phase

with F_B. If a polar diagram is plotted a pattern will be obtained which has a big lobe on one side and a small one on the other as shown in Figure 3D. If for commutation of the field pattern the phase of the current in the centre aerial, or in both outer aerials, is reversed by 180° the diagram will be reversed, the large lobe being replaced by the small one and vice versa, thus producing the well known overlapping field patterns with the equi-signal line along BP (Figure 3D). Technically it is very difficult to obtain 180° phase shift without complicated electronic keying equipment or timed change over relays, the latter leading to difficulties due to a third field pattern during the change over just as in the known system utilising reflectors. However, by using a phase shift of less than 180° the problem is greatly simplified. In practice about 90° is used. This solution has only two disadvantages.

1. The beam width is slightly broader than it would be if 180° phase change were used. More power has, therefore, to be fed into the outer dipoles, in order to get a beam of a given width, than would be necessary with 180° phase change.

2. This means that the "on course" signal is less than it would be with 180° phase change. However, compared to the keyed reflector system the 3 antenna system with 90° keying is at no disadvantage in this respect as the greater dipole spacing that is possible with the system according to this invention helps to give a narrower beam.

2. The phase change of 90° of the current in the centre dipole is obtained by shunting the latter with a reactance which is changed from a capacitive to an inductive value with keying. This throws a load back onto the transmitter which varies with keying, so that if the output circuit is badly mistuned it is possible to change the orientation of the beam. If this possibility is realised, and the values of reactance are kept small, the change of orientation may be made negligible. Field tests show that very bad mistuning of the transmitter gives a maximum change of not more than .4° in orientation. Normal tuning adjustments are not likely to give more change than 1°.

Keying with 90° phase change

Referring now to Figure 4, A, B and C are 3 dipoles fed with current in relative phase of 0° 45° 180° as shown in Figure 4A. On keying, as hereinbefore described in relation to Figure 2, the phase of the centre dipole current is changed by 90° giving the relative phases of 0° 315° 180°. At P we therefore have the field from the centre aerial alone producing a signal since the fields from the outer dipoles cancel. On moving to P₁ we have the field F_B from B, and the resultant F_{AC} of the fields from A and C as shown in Figure 4C. These add up vectorially and produce a field pattern as shown in Figure 4D in full line. On changing the phase of the centre aerial current by 90° the pattern is reversed, as shown in Figure 4D dotted line.

The advantages of the beacon according to the present invention are:

1. The beam width can be set up to any required value.
2. A single contact relay is used for keying, thus eliminating timed relays and the possibility of key clicks. Good back and front beams will always be obtained.
3. The field radiated is concentrated in the direction of the beam rather than to the sides.

This reduces the likelihood of split beams as they are usually caused by reflections from objects situated on either side of the course.

4. The antenna system is very simple both in construction and operation and does not require highly skilled personnel to maintain it. The system can be easily set up on a new operating frequency from written instructions.

What is claimed is:

1. A radio beacon for radio guiding systems of the kind in which a field distribution or field strength pattern is commutated so as to produce complementary signals to the right and left of the course respectively, and on the course a continuous dash or no signal, comprising three linear antennae mounted above the ground and symmetrically located with respect to the desired course, means for feeding the outer antennae with currents in opposite phases and for feeding the centre antenna with currents of the same frequency and with a phase angle of 90 degrees or less with respect to the currents in either of the two outer antennae, and means for changing the relative phases of the centre and outer antennae from a phase lead to a phase lag or vice versa to produce the commutation of the field strength pattern.

2. A radio beacon for radio guiding systems of the kind in which a field distribution or field strength pattern is commutated so as to produce complementary signals to the right and left of the course respectively and on the course a continuous dash or no signal, comprising three antennae arranged at a distance apart and each fed directly from a source of high frequency currents phased with respect to each other, a network associated with one of said antennae for effecting a phase lag or a phase lead of approximately 90° in the excitation of said one antenna with respect to the other antenna, and a single "make" or "break" contact device for changing the said network to control the said lead or lag excitations and thereby for commutating the field strength pattern formed by said antennae.

3. A radio beacon for radio guiding systems of the kind in which a field distribution or field strength pattern is commutated so as to produce complementary signals to the right and left of the course respectively and on the course a continuous dash or no signal, comprising three dipole antennae mounted above the ground in alignment perpendicular to the desired course, the two outer antennae being at equal distances from the course line and the centre antenna being on the course line, means for feeding the two outer dipoles with currents in phase opposition and for feeding said centre dipole with currents of the same frequency and having a phase angle with respect to the currents in either of the outer dipoles of 90° or less, and means for changing the

phase relationships of the currents in the outer and centre dipoles from a phase lead to a phase lag and vice versa.

4. A radio beacon as claimed in claim 3 wherein in the phase angle of the current in the centre dipole is at 90° with respect to the currents in the outer dipoles and means are provided for reversing said phase angle alternately to produce the commutation.

5. A radio beacon as claimed in claim 3 wherein in the phase angle of the current in the centre dipole is at 45° with respect to the current in one of said outer dipoles and means is provided for changing said phase angle by 90° to change said phase angle from a lead to a lag and vice versa.

10 6. A radio beacon as claimed in claim 3 wherein the phase angle of the current in the center dipole is at 45° with respect to the current in one of said outer dipoles, including a capacity of the 20 same impedance magnitude as the resistance of the center dipole, means for connecting said capacity in shunt across said center dipole, and further means for periodically short circuiting said capacity so as to render said dipole alternately capacitive and inductive, whereby phase lag and phase lead are produced in said center dipole.

7. A radio beacon as claimed in claim 3 wherein in the phase angle of the current in the center 30 dipole is at 45° with respect to the current in one of said outer dipoles, including a capacity of the same impedance magnitude as the resistance of the center dipole means for connecting said capacity in shunt across said center dipole, and further 35 means for periodically short circuiting said capacity so as to render said dipole alternately capacitive and inductive, said further means comprising a single pole "make" and "break" contact device, the "make" contact producing phase lag 40 and the "break" contact producing phase lead.

8. A radio beacon for radio guiding systems of the kind in which a field strength pattern is commutated so as to produce complementary signals to the right and the left of the course respectively 45 and on the course a continuous dash or no signal, including three antennae arranged at a distance apart and each fed directly from a source of high frequency currents differentially phased with respect to each other, and a single "make" or 50 "break" contact device for commutating the field strength pattern formed by said antennae, said contact device comprising an electromagnetic phase shifting relay located adjacent to one antenna, keying means located adjacent said source 55 of high frequency currents, and means for transmitting relay energizing current over the same line by which said center dipole is fed.

LOUIS JOHN HEATON-ARMSTRONG.
